ANCHOR MEANS FOR WALLET POCKETS

Louis Seamon, Brooklyn, N. Y.

Application February 3, 1951, Serial No. 209,242

5 Claims. (Cl. 150—38)

1

This invention relates to wallets, billfolds and the like.

An object of this invention is to provide a novel and improved pocket construction for wallets or similar articles.

A further object hereof is to provide pocket constructions for wallets made of plies of sheet material associated in a novel and improved manner especially adapted for single or double card carrying pockets usually incorporated in wallet structures.

Still a further object hereof is to provide a novel pocket construction of the character mentioned which is cheap and easy to manufacture and efficient in carrying out the purposes for which they are designed.

Still a further object of this invention is to provide methods for anchoring the pocket material. This anchor not only improves the construction but reinforces the pocket and maintains its correct form and allows more cards to be placed into the pocket. This construction also makes it possible to make the pockets with a great deal less material since a required lap over can be made considerably shorter because of the novel anchoring means herein employed.

This application is a continuation in part of my application Serial No. 127,046, filed November 14, 1949, now abandoned.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a plan view of an assembled wallet having anchored pockets embodying the invention.

Figure 2 is a cross-sectional view taken on line 2—2 in Figure 1.

Figure 3 is a view showing the wallet shown in Figures 1 and 2 in partly folded position and showing a double tongue and groove anchoring arrangement.

Figure 4 is a view of a blank from which the wallet shown in Figures 1 to 3 inclusive is made.

Figure 5 is a plan view of a modified assembled wallet embodying the invention.

Figure 6 is a cross-sectional view taken on line 6—6 in Figure 5.

Figure 7 is a view showing the wallet shown

2

in Figures 5 and 6, in partly folded position, and showing a two-piece anchor and strap stitched together.

Figure 8 is a plan view of a blank from which the wallet shown in Figures 5 to 7 inclusive is made.

Figure 9 is a plan view of another modified assembled wallet embodying the invention.

Figure 10 is a cross-sectional view taken on line 10—10 in Figure 9.

Figure 11 is a view showing the wallet shown in Figures 9 and 10, in partly folded position, and showing a one-piece anchor and strap glued together.

Figure 12 is a plan view of a blank from which the wallet shown in Figures 9 to 11 inclusive is made.

Figure 13 is a plan view of another modified assembled wallet embodying the invention.

Figure 14 is a cross-sectional view taken on line 14—14 in Figure 13.

Figure 15 is a view showing the wallet shown in Figures 13 and 14, in partly folded position, and showing a one-piece anchor sewed to the center walls of the pockets.

Figure 16 is a plan view of a blank from which the wallet shown in Figures 13 to 15 inclusive is made.

In the illustrated embodiment of the invention, 30 the numeral 10 indicates a wallet or billfold made from a blank 11 cut from a strip of leather or other flexible material suitable for the purpose.

The blank 11 includes a rectangular portion 12 which forms the rear or outer wall of the billfold and which is provided intermediate its ends with transverse fold lines 13 defining a central hinge.

Integrally connected to the lower edge of the wall 12 and arranged on opposite sides of the fold lines 13 are two flaps 14 and 15, each of which is foldable along a line 16 upwardly upon the wall 12.

The flaps 14 and 15 form the front walls of card carrying pockets 17 and 18. The flap 14 has 45 foldably connected to its lower edge a section 20 adapted to be folded along a line 21 upwardly and over and rearwardly upon the flap 14. The flap 15 has foldably connected to one edge a section 23 adapted to be folded along a line 24 upwardly and over and rearwardly upon the flap 15. The lines 21 and 24 are in alignment.

A transparent window 25 is formed in the flap 14 so as to allow reading of an identification card (not shown) without removing it from the 55 pocket 17.

This invention is particularly directed to the construction of a center anchor 30 for interengagement with the rear portion of the pocket material, that is, with the sections 20 and 23. The anchor 30, as shown in Figure 4, is bifurcated and consists of two branches or forks 31 having tongues or fingers 32 extending laterally toward each other.

In the partly folded position of the wallet, shown in Figure 3, the tongues 32 are shown in interengagement with grooves or openings 34, 34, laterally positioned in the sections 20 and 23. (See Figure 4.)

In this interengaged position, the latch-shaped fingers 32 hold and prevent the rear portion of the pocket material from lifting up and thus maintain the shape of the pockets 17 and 18.

In the assembled position shown in Figures 1 and 2, a stay or panel 35 is placed rearward of the flaps 14 and 15 and conceals the center anchor.

It is to be noted that the forks 31 of the anchor 30 are preferably made slightly longer than that required. These extra lengths of the forks make it possible for the fingers 32 to slide in the openings 34. There is thus provided a yieldable interengagement which permits the forks to slide slightly through the openings.

When an excess of cards are placed in the pockets 17 and 18, the forks are pulled out slightly from the openings 34 till the fingers 32 come into engagement with the walls defining said openings and this stops further enlargement of the pockets. This arrangement provides means for taking care of an overcrowding of the pockets without spoiling their appearance. It is to be noted that while the wallet disclosed herein is designed to take care of an excess of cards or other articles placed in the pockets, that the anchor piece remains in operation at all times, even when there is no excess of articles in the pockets.

The billfold 40 has end flaps 37 which in assembled relation are folded over and glued to the flaps 14 and 15. A top flap 39 is also used and is folded over and glued to the inner surface of the outer wall 12.

As shown in Figures 5 to 8 inclusive, there is provided a modified wallet or billfold 40 made from a blank 41 cut from a strip of leather or other flexible material suitable for the purpose.

The blank 41 includes a rectangular portion 42 which forms the outer wall of the billfold and which is provided intermediate its ends with transverse fold lines 43 defining a central hinge.

Integrally connected to the lower edge of the wall 42 and arranged on opposite sides of the fold lines 43 are two flaps 44 and 45, each of which is foldable along a line 46 upwardly upon the wall 42.

The flaps 44 and 45 form the front walls of card carrying pockets 47 and 48. The flap 44 has foldably connected to its lower edge a section 50 adapted to be folded along a line 51 upwardly and over and rearwardly upon the flap 44. The flap 45 has foldably connected to its lower edge a section 53 adapted to be folded along a line 54 upwardly and over and rearwardly upon the flap 45. The lines 51 and 54 are in alignment.

It is to be noted that the sections 50 and 53 are integrally connected with a central bar portion 55. This modified form of the invention is particularly directed to the construction of a center anchor 60 for interengagement with the rear portion of the pocket material, that is, with the

sections 50 and 53. The anchor 60, as shown in Figure 8, is bifurcated and consists of two branches or forks 61.

In the partly folded position of the wallet, shown in Figure 7, the forks 61 are stitched to the central bar portion 55 by stitching 62. In this interengaged position, the forks 61 hold and prevent the rear portion of the pocket material from lifting up and thus maintain the shape of the pockets 47 and 48. In the assembled position shown in Figures 6 and 7, a stay or panel 65 is placed rearward of the flaps 44 and 45 and conceals the center anchor 60.

The modified billfold 40 has end flaps 67 and 68 which in assembled relation are folded over and pass through slots 69 and 70 respectively, and are retained in assembled relation thereby. A top flap 71 is also used and is folded over and glued to the inner surface of the outer wall 42. In assembled relation, the sections 50 and 53 are secured by stitching 73 to the flaps 44 and 45 respectively.

As shown in Figures 9 to 12 inclusive, there is provided another modified wallet or billfold 80 made from a blank 81 cut from a strip of leather or other flexible material suitable for the purpose.

The blank 81 includes a rectangular portion 82 which forms the outer wall of the billfold and which is provided intermediate its ends with transverse fold lines 83 defining a central hinge.

Integrally connected to the lower edge of the wall 82 and arranged on opposite sides of the fold lines 83 are two flaps 84 and 85, each of which is foldable along a line 86 upwardly upon the wall 82.

The flaps 84 and 85 form the front walls of card carrying pockets 87 and 88. The flap 84 has foldably connected to its lower edge a section 90 adapted to be folded along a line 91 upwardly and over and rearwardly upon the flap 84. The flap 85 has foldably connected to its lower edge a section 93 adapted to be folded along a line 94 upwardly and over and rearwardly upon the flap 85. The lines 91 and 94 are in alignment.

It is to be noted that the sections 90 and 93 are integrally connected with a central bar portion 95. This modified form of the invention is particularly directed to the construction of a bar type center anchor 100 for interengagement with the bar portion 95. The anchor 100, as shown in Figure 12, has a portion folded over on line 101 and glued to the bar portion 95, as shown in Figure 11.

In this interengaged position, the anchor 100 holds and prevents the rear portion of the pocket material from lifting up and thus maintains the shape of the pockets 87 and 88. In the assembled position shown in Figures 10 and 11, a stay or panel 105 is placed rearward of the flaps 84 and 85 and conceals the center anchor 100.

The modified billfold 80 has end flaps 107 and 108 which in assembled relation are folded over and pass through slots 109 and 110 respectively and are retained in assembled relation thereby.

A top flap 111 is also used and is folded over and glued to the inner surface of the outer wall 82. In assembled relation, the sections 90 and 93 are secured at their outer ends by stitching 113 to the flaps 84 and 85 respectively.

As shown in Figures 13 to 16 inclusive, there is provided another modified wallet or billfold 120 made from a blank 121 cut from a strip of leather or other flexible material suitable for the purpose.

The blank 121 includes a rectangular portion 122 which forms the outer wall of the billfold and which is provided intermediate its ends with transverse fold lines 123 defining a central hinge.

Integrally connected to the lower edge of the wall 122 and arranged on opposite sides of the fold lines 123 are two flaps 124 and 125, each of which is foldable along a line 126 upwardly upon the wall 122.

The flaps 124 and 125 form the front walls of card carrying pockets 127 and 128. The flap 124 has foldably connected to its lower edge a section 130 adapted to be folded along a line 131 upwardly and over and rearwardly upon the flap 124. The flap 125 has foldably connected to its lower edge a section 133 adapted to be folded along a line 134 upwardly and over and rearwardly upon the flap 125. The lines 131 and 134 are in alignment.

This modified form of the invention is particularly directed to the construction of a modified bar type center anchor 140 for interengagement with the rear portion of the pocket material, that is, with the sections 130 and 133. The anchor 140, as shown in Figure 15, is secured by stitching or stapling 145 to the sections 130 and 133.

In this interengaged position, the anchor 140 holds and prevents the rear portion of the pocket material from lifting up and thus maintains the shape of the pockets 127 and 128. In the assembled position shown in Figures 13 and 14, a stay or panel 146 is placed rearward of the flaps 124 and 125 and conceals the center anchor 140.

The modified billfold 120 has end flaps 147 and 148. The flap 147 is folded over and passed through a slot 149 and is retained in assembled relation thereby. The flap 148 is folded over and retained in assembled relation to the flap 125 by a snap fastener 150.

A top flap 151 is also used and is folded over and glued to the inner surface of the outer wall 122. In assembled relation the sections 130 and 133 are secured at their outer ends by stitching 153 to the flaps 124 and 125 respectively.

It is to be noted that each wallet structure herein disclosed includes a stay and a sheet member forming a pocket with the stay. The sheet member is folded and free around the stay along one side edge of the pocket.

It is also to be noted that the invention herein disclosed may be utilized for anchoring two pockets positioned at the central portion of the wallet or for anchoring a single pocket forming part of the wallet.

In accordance with the patent statutes I have described and illustrated the preferred embodiments of my invention, but it will be understood that various changes and modifications can be made therein without departing from the spirit of the invention as defined by the appended claims.

I claim:

1. In a wallet having at least one anchored pocket, comprising a rear wall and a front wall, and a stay rearward of said front wall; an edge portion of said front wall being folded around said stay to provide an overlapped portion, an-

chor means integral with and extending from the bottom of said rear wall in interengagement with said overlapped portion of said front wall, thereby preventing said overlapped portion from lifting up from the rear of said stay, and preventing deformation of said pocket.

2. In a wallet having at least one anchored pocket comprising a rear wall and a front wall and a stay rearward of said front wall; an upper edge portion of said front wall being folded around said stay to provide an overlapped portion, bifurcated anchor means integral with and extending from the bottom of said rear wall in interengagement with said overlapped portion of said front wall, the free end portion of said anchor means having latch fingers, said overlapped portion having openings adapted to receive said fingers, preventing said overlapped portion from lifting up from said stay, thereby preventing deformation of said pocket.

3. A wallet having an anchored pocket comprising a rear wall and a front wall, and a stay rearward of said front wall; said stay extending along one longitudinal edge of said pocket, an upper edge portion of said front wall being folded around said stay to provide an overlapped portion of said front wall, and an anchor extending from the bottom of said rear wall and secured to said overlapped portion.

4. A wallet having an anchored pocket comprising a rear wall and a front wall, and a stay rearward of said front wall; an edge portion of said front wall being folded around said stay to provide an overlapped portion, and an element connecting said overlapped portion of said front wall to said rear wall for reinforcing and preventing deformation of said pocket.

5. In a wallet having at least one anchored pocket, comprising a rear wall and a front wall, and a stay rearward of said front wall; an edge portion of said front wall being folded around said stay to provide an overlapped portion having openings, anchor means integral with and extending from the bottom of said rear wall in interengagement with said overlapped portion of said front wall, thereby preventing said overlapped portion from lifting up from the rear of said stay, and preventing deformation of said pocket, said anchor means having forks of a length permitting sliding of the ends thereof through said openings, causing yieldable interengagement of said anchor means with said overlapped portion.

LOUIS SEAMON.
